SPACE-CHARGE TUBE

William S. Brian, Great Neck, N. Y., assignor to
 Hanson-Gorrill-Brian, Inc., Glen Cove, N. Y.,
 a corporation of New York

Application January 6, 1948, Serial No. 693

5 Claims. (Cl. 250—27.5)

1

This invention relates to vacuum tubes, and more particularly to vacuum tubes utilizing a space-charge grid.

The use of the first grid of a multi-grid vacuum tube as a so-called "space-charge grid," to overcome the space-charge surrounding the electron emitter and consequently lower the internal resistance of the tube, has been known for many years. This result is achieved by operating the first grid at a positive potential with respect to the cathode or other electron emitting element in the vacuum tube. However, the first grid in standard tubes is physically so close to the cathode that it draws excessive current when it is operated with enough positive voltage to perform its function as a space charge grid satisfactorily. Because of this defect with conventional tubes their use as space-charge grid tubes has been discarded, even though there are many advantages to such tubes.

The object of the present invention is, therefore, to provide a novel space-charge grid tube in which the first or space-charge grid is so spaced and so shielded from the electrons leaving the cathode that it can be operated with sufficient positive voltage on the space-charge grid without drawing excessive current.

A further object of the present invention is to provide means for constructing a virtual cathode having a large area without consuming an excessive amount of power.

A still further object of the present invention is to decrease the internal resistance of the tube by efficiently overcoming the space charge surrounding the electron emitter.

Still another object is to provide a novel vacuum tube especially useful as an audio frequency amplifier, producing a minimum amount of distortion.

A further object of the present invention is to provide a circuit for utilizing the advantages of such a tube and minimize the change in the tube's transconductance due to change in grid bias.

These and other advantageous objects are obtained in a tube built in accordance with the present invention by providing a plurality of shield or electron deflecting rods interposed between the cathode or other electron emitting surface and the members supporting the first or space-charge grid. Since this grid is operated at a positive potential with respect to the cathode, the electrons emitted from the cathode are attracted thereto. However, a great many such electrons strike the members supporting

2

the grid structure and are conducted away in the form of grid current. Such current not only is undesirable in that it causes excessive heating of the grid, but it causes the tube to be inefficient and uneconomical to operate.

By providing shield rods between the cathode and the grid, the path of the emitted electrons may be directed so that a great percentage of them pass between the interstices of the space-charge grid structure and a minimum number strike the grid supporting members.

The operation of the present invention will become more apparent from the following detailed description of the tube structure and operation taken in connection with the drawings wherein:

Fig. 1 is a cut-away view of one type of electron tube constructed in accordance with the present invention;

Fig. 2 is a cross-section of the tube shown in Fig. 1 taken on the line 2—2 of Fig. 1; and

Fig. 3 is a schematic circuit showing the tube connected as a voltage amplifier.

Referring now more particularly to Fig. 1 which shows a cut-away of a tube constructed in accordance with the present invention. Rod-like cathode 10 can be seen to be surrounded by a set of three coaxial grids 11, 12 and 13 which may be of the helical type. Each of these grids is supported respectively by rod-like members 11', 12', and 13' oriented parallel to cathode 10. Shield rods 17 can be seen mounted parallel to the cathode 10 and positioned between it and rod-like members 11' supporting the first or inner-most grid 11. Conventional cylindrical anode 14 surrounds the grid and cathode structure, and the whole assembly is supported within metallic envelope 15. The lead-in wires to the various elements are connected to their respective pins 16 at the base of the tube structure. Although, the embodiment shown in Fig. 1 is of the screen grid type tube having a metallic envelope, the invention may, of course, be applied to tubes having a different number of electrodes and utilizing envelopes made of glass.

Fig. 2 shows a cross-section of the tube shown in Fig. 1. As in Fig. 1, it can be seen that cathode 10 heated by heater 22 is surrounded by grids 11, 12 and 13. These grids are shown to be oval in cross-section which permits of great mechanical rigidity, although they might easily be constructed having other shapes. Cylindrical anode 14 is shown surrounding the cathode 10 and grids 11, 12 and 13. The supporting members 11', 12' and 13' are shown all oriented

in a plane with cathode 10 and another supporting member 14. In this same plane, shield rods 17 may be seen interposed between cathode 10 and grid 11.

In operation, first grid 11 is made positive with respect to cathode 10. Its effect is thus to counteract the effect of the negative space charge which surrounds an electron emitter such as cathode 10 and to produce a cloud of electrons at the plane of the first grid. This cloud acts as a virtual cathode. The operation of such a tube is similar to that of a tetrode having a large effective cathode area behaving as if it were temperature limited. Grid 12 is used as the control or signal grid and grid 13 is operated as a screen grid. Although no suppressor grid is shown, such a grid may be used to prevent the secondary electrons from anode 14 from returning to grid 13.

To reduce the space-charge grid current, the two side rods or shield members 17 are utilized. These rods or members 17 could be electrically connected to either the cathode 10 or the control grid 12. By thus restricting the path of electrons to the vicinity of the lateral wires of the space-charge grid 11, its current is considerably reduced with the resultant increase in efficiency. The magnitude of this increased efficiency is considerable since the area of supporting rods 11' which would intercept emitted electrons is greater than the combined area of all the useful field-producing lateral wires of grid 11. Thus, the total current of the space-charge grid 11 is greatly reduced by the utilization of shield rods or members 17 without in any way damaging the electrical performance of the tube.

Fig. 3 shows the tube of Figs. 1 and 2 in a schematic form connected in a voltage amplifier circuit. An alternating input signal is applied to control grid 12 through coupling condenser 20. Resistor 21 is connected between control grid 12 and ground. Cathode 10 is heated by heater 22 which has a source of potential 23 applied to heater leads 24 and 25. Cathode bias resistor 26 is connected between cathode 10 and ground, and is by-passed in conventional manner by cathode by-pass condenser 27. Anode 14 is connected to B+ through plate load resistor 28. Resistor 29 connected between B+ and screen grid 13, and by-pass condenser 30 connected between screen grid 13 and ground serve as a conventional screen grid supply filter. Positive voltage is applied to space-charge grid 11 through voltage dropping resistor 31 connected to B+. Shield rods 17 are conductively connected together and in turn are connected to control grid 12. Condenser 32 serves to couple the amplified signal from the plate end of plate load resistor 28 to the succeeding stage.

It will be noted that the voltage for the space-charge grid 11 is obtained from the normal anode supply through the series dropping resistor 31 which has no by-pass condenser across it. Since the space-charge grid current tends to increase as the control grid bias is more negative, the voltage drop through resistor 31 is increased, with the result that the positive voltage on space charge grid 11 is reduced. This causes greater than normal reduction in the plate current resulting in an increased transconductance in the negative bias region. When the control grid 12 is made less negative, that is, when the control grid bias is made less negative, the space-charge grid current is decreased. This decrease causes less voltage drop across resistor 31 thereby in-

creasing the positive voltage on space-charge grid 11 and increasing the plate current. Thus, the result of such operation is to reduce distortion resulting from a change in transconductance with changing grid bias.

From the above it will be seen that a tube built in accordance with the teachings of my invention results in a tube having an extremely low internal resistance. By the use of the shield rods, as described, this advantage is achieved in an efficient manner. Furthermore, if such a tube is utilized in a circuit such as described, the change in tube transconductance due to a change in grid bias is minimized thereby resulting in distortion reduction.

Since many changes could be made in the above construction and many apparently widely different embodiments of this invention could be made without departure from the scope thereof, it is intended that all matter contained in the above description or shown in the accompanying drawings shall be interpreted as illustrative and not in a limiting sense.

What is claimed is:

1. An electronic circuit comprising, an electron tube comprising a cathode, a space-charge grid surrounding said cathode, a control grid surrounding said space charge grid, a screen grid surrounding said space-charge grid, an anode surrounding said screen grid, and a pair of shield rods positioned between said space-charge grid and said cathode, a source of potential having its negative terminal grounded, a first impedance element connected between the positive terminal of said source of potential and said space-charge grid, a second impedance element connected between said positive terminal and said screen grid, a third impedance element connected between said positive terminal and said anode, a fourth impedance element connected between said control grid and ground, and a conductive connection between said control grid and said shield rods, said impedance elements cooperating with said shield rods in use to minimize changes in tube transconductance with changes in operating grid bias.

2. An electronic circuit comprising an electron tube having a cathode, a plurality of accelerating grids, a control grid, an anode, and a plurality of electron repelling members surrounding said cathode, a plurality of resistances, a source of potential having its negative terminal grounded and its positive terminal connected through a respective one of said resistances to said plurality of accelerating grids, and a conductive connection between said electron repelling members and said control grid, said resistances operating in conjunction with said repelling members to minimize changes in tube transconductance with changes in operating grid bias.

3. An electronic circuit comprising, an electron tube comprising a cathode, a space-charge grid surrounding said cathode, shield rods located between said cathode and said space-charge grid, a control grid surrounding said space-charge grid and an anode surrounding said control grid, a source of potential connected to said anode, and impedance elements connected between said source of voltage, the anode and said space-charge grid, said impedance elements serving in conjunction with said shield rods to minimize changes in tube transconductance due to changes in bias of said control grid.

4. An electron tube comprising a cathode, a positive grid surrounding said cathode, said posi-

tive grid having supporting members, shield members interposed between said cathode and said grid supporting members for reducing the space-charge grid current of the tube, a control grid surrounding said positive grid, said positive grid serving in use to counteract the effect of the negative space charge surrounding the cathode by producing a region of positive charge around the latter, and an anode surrounding said control grid.

5. An electron tube comprising a cathode, a positive helical grid surrounding said cathode, said positive grid having supporting rods, a pair of shield rods interposed between said cathode and said supporting rods for reducing the space-charge grid current of the tube, a helical control grid surrounding said positive grid, said positive grid serving in use to counteract the effect of the negative space charge surrounding the cathode by producing a region of positive charge this serving as a virtual cathode, a screen grid surrounding

said control grid and an anode surrounding said screen grid.
